METHOD OF SEAMING COVER ENDS TO
CAN BODIES

John Henchert, Chicago, Ill., assignor to Continental Can Company, Inc., New York, N. Y., a corporation of New York

Application June 19, 1941, Serial No. 398,830

1 Claim. (Cl. 113—121)

The invention relates to new and useful improvements in a method of seaming a cover end to a can body of the type shown and described in the patent granted C. A. Arnesen April 9, 1940, No. 2,196,181.

An object of the invention is to provide a method of making an end seam of the above type whereby the end seam is so constructed as to make a tight seal for the can body and at the same time provide a space in the end seam which facilitates the cutting of the metal so as to separate the cover end from the can body.

In the drawings:

Figure 1 is a sectional view through a portion of a cover end as initially die-shaped, which cover end is to be seamed to the can body by the improved method.

Figure 2 is a similar view but showing the cover end flange subjected to a curling roll for curving the edge portion outwardly and inwardly to a point substantially in alignment with the bottom wall of the depression in the cover end.

Figure 3 is a view of the cover end similar to Figure 2 but showing the flange coated with a sealing material and also showing the cover end as applied to a flanged can body preliminary to the joining of the seam thereto by a double seam.

Figure 4 is a view showing the cover end flange subjected to the first seaming operation wherein the outer portion of the flange is bent downwardly while the body flange still remains in its initial position.

Figure 5 is a view similar to Figure 4 but showing the end seam subjected to a second operation seaming roll for tucking the outer portion of the end flange underneath the flange on the can body and into contact with the under side of the base of the body flange while leaving the lowermost portion of the end seaming flange spaced away from the body flange.

Figure 6 is a view similar to Figure 5 but showing the end seam as subjected to a seaming roll for pressing the body flange and a portion of the cover end flange into tight engagement with each other and the body wall in the region extending from the lower edge of the body flange upwardly while providing a space in the seam beneath the lower edge of the body flange.

In carrying out the improved method, the can body 1 is provided with an outwardly turned flange 2. The cover end which is to be seamed to this body flange is shown at 3 in the drawings; said cover end is provided with the usual depression which is surrounded by a vertical wall 4 adapted to fit within the can body; said cover

end has an outwardly extending seaming flange 5 which projects to a distance beyond the outer edge of the body flange 2 more than twice the length of the flange as shown in Figure 3 of the drawings. Said seaming flange inclines downwardly from the base 6 of the flange toward the outer edge thereof and the outer edge portion is turned sharply downward as indicated at 7. The cover end as thus described and as shown in Figure 1 is die shaped by the usual form of shaping dies.

The cover end 3 is then subjected to a curling roll 8 and the edge portion 9 thereof is curled downwardly and inwardly so that the lower edge 10 of the curl is substantially in a line containing the bottom wall of the depression in the cover end. After the edge portion of the seaming flange has been curled in the manner described then a coating 11 of any suitable sealing material is applied to the under side of the cover end flange and the inner side of the curled portion 9. This coating may be applied before the edge portion of the cover end is curled. The cover after it is shaped in the manner above described is placed on the can body 1, after which the can body is chuck and the outer edge portion of the cover end flange is subjected to a seaming roll 11. This seaming roll is of the usual character except as to shaping and is caused to move relative to the can body and the cover end flange so as to perform the initial steps in a seaming operation. This seaming roll 11 is shaped so that when the seaming operation performed thereby is finished the outer portion of the cover end flange will be given the shape shown in Figure 4. It will be noted that the flange along the line 12 is sharply bent downwardly without any material change in the shape of the curled edge portion.

After this initial seaming operation shown in Figure 4, then the cover end flange is subjected to a seaming roll 13 having a groove shaped so that when the seaming operation of this roll is completed the seam parts will be shaped as shown in Figure 5. It will be noted that the outer portion of the cover end flange has been tucked underneath the body flange and the edge 14 thereof brought into contact with the under side of the base 6 of the cover end flange. It will also be noted that this tucked under portion is spaced away from the body flange 2 and is spaced a considerable distance below the end of the body flange as indicated at 15.

After completing the second seaming operation illustrated in Figure 5, then the seam parts are subjected to another seaming roll 16 which is

shaped so that when it has completed its seaming operation the portion 17 of the cover end flange is brought into intimate contact with the flange 2 of the can body and the flange 2 of the can body is brought into intimate contact with the innermost portion of the cover end flange and said innermost portion of the cover end flange is brought into intimate contact with the body wall of the can. This makes a very tight seam. While these parts are brought into tight contact for sealing the can, the lowermost portion of the can end flange is still spaced away from the lower end of the flange 2 of the can body and is shaped so as to provide a recess or space 13. This recess or space extends outwardly beyond the body flange so that when a can opening cutter wheel is applied to the lower face 19 of the seam, the wall may be cut through and the outer portions of the cover end flange forced outwardly so as to release the cover end from the can body.

It will be noted that in the illustrations shown in Figures 4, 5 and 6 the sealing material has been omitted for the sake of clearness. It will also be noted that the shaping of the seam is accomplished by seaming rolls which operate progressively to first bend the flange of the cover end without disturbing the initial position of the body flange, then to tuck the outer portion of the cover end flange underneath the body flange while it is still spaced away from the body wall, and then to finally shape the parts to produce a very tight seam while leaving a recess or space which extends outwardly along the bottom edge portion of the seam and below the body flange.

It is obvious that minor changes in the details of construction and the shaping of the parts may

be made without departing from the spirit of the invention as set forth in the appended claim.

I claim:

5 The method of seaming a cover end to a can body, consisting in outwardly flanging the body, die shaping a cover end dimensioned so as to provide a central depressed portion and a seaming flange of more than twice the length of the body flange, which cover flange is initially inclined 10 downwardly from the base of the flange to the outer edge thereof, subjecting the outer edge portion of the cover end to a curling roll for curving said edge portion downwardly and inwardly to a point substantially in alignment with the bottom 15 wall of the depression, placing the cover end on the can body and subjecting the cover end flange to a seaming roll shaped so as to bend the outer portion of the flange downwardly while the body flange remains in its initial position, then subjecting said cover end flange to a second seaming 20 roll shaped so as to tuck the outer portion of the flange underneath the flange on the can body into contact with the under side of the base of the body flange while leaving the lowermost portion 25 of the cover end seaming flange spaced away from the body flange, and projecting below and spaced away from the lower edge of the body flange and finally subjecting said initially seamed parts to a third seaming roll shaped so as to press the body flange and a portion of the cover end flange into tight engagement with each other and the body wall in the region extending from the lower edge of the body flange upwardly while providing a space in the seam beneath the lower 30 edge of the body flange.

JOHN HENCHERT.
